M. H. Gates,
Dentists' Tooth Drill.
No. 58,631. Patented Oct. 9, 1866.

UNITED STATES PATENT OFFICE.

WILLIAM H. GATES, OF LOUISVILLE, KENTUCKY.

IMPROVEMENT IN DENTAL DRILLS.

Specification forming part of Letters Patent No. 58,631, dated October 9, 1866.

To all whom it may concern:

Be it known that I, WM. H. GATES, of Louisville, in the county of Jefferson and State of Kentucky, have invented a new and useful Improvement in Drills; and I do hereby declare that the following is a full, clear, and exact description thereof, which will enable others skilled in the art to make and use the same, reference being had to the accompanying drawings, forming a part of this specification, in which—

Figure 1 represents a vertical section of my improved drill on the line F F, Fig. 2, shown in operation. Fig. 2 is a side view of my improved drill in the pointed bulb-shaped form. Fig. 3 is an instrument with but two of the described blades. Fig. 4 is a vertical section of same through b b.

Similar letters of reference indicate like parts.

The object of my invention is to combine the efficiency of the ordinary drill with the steady movement of the reamer, so as, in enlarging perforations, to operate as an improved self-clearing reamer, and, through solid material, as an improved drill, to make and finish these perforations at the same time, and separated by deep undercut grooves running spirally or diagonally to its stem, for the free removal of its cuttings.

It consists of two or more blades formed in the surface of a bulb or pointed bulb-shaped head of steel or other drill material, the blades being beveled off backward, parallel from the cutting-edge, in proportion to the chip or shaving cut or the resistance encountered, so that in operating they constantly glide against that portion of material which the next blade will cut away, and thus render the movement of the instrument uniform and reliable. For this reason, in many places where other drills would be broken, this drill may be employed with safety in passing through fissures, &c., or, in a very attenuated form, with two or three blades and a flexible stem, in enlarging the devious and often flattened canals of the pulp in the roots of necrosed teeth. For this purpose it should have a bulb shape and conical point, which, followed by the flexible stem, will guide it suc-

cessfully through all the ordinary devious canals above mentioned. It being a matter of vital importance in the treatment of these roots that the canals should be sufficiently enlarged to admit of being properly filled without producing the least pneumatic effect through them on the tissues beyond, it is claimed that this instrument accomplishes that result, at the same time clearing itself of its cuttings, and the canal of its deteriorated fluids, instead of, piston-like, forcing them through the foramen to create or aggravate disease.

As the line of the general surface or lowest point or edge of each blade (which may be straight from B to H) is always exterior to or above a line drawn from its edge to the edge of the blade adjacent, it may with care be sharpened without touching the latter; but by means of pliers constructed with blades crossing each other diagonally at their occlusion, it may be firmly held and readily sharpened while each edge is successively protected by the same.

A, Fig. 1, is a portion of brass or other material, in which a section of the drill is shown operating; A', its finished border; B, the cutting-edges of the drill, Figs. 1 and 2; a, Fig. 1, the shaving or portion which B will cut, and against the inside of which the blade-surfaces C move steadily; D, the grooves for removal of cuttings; H, the inferior edge or border of the blade-surfaces. E, Fig. 2, is the stem of the drill; F F, line of section shown in Fig. 1.

I claim—

A drill-head having two or more of the longitudinally curved external surfaces, C, extending from B to H, in conjunction with an equal number of cutting-edges, undercut by deep grooves running backward from the end spirally or diagonally to the stem or axis, substantially as described, and for the purpose set forth.

W. H. GATES.
